Primary Examiner—Nelson C. Holtje

(57) **CLAIM**

The ornamental design of a combined snowmobile ski and handle, as shown and described.

DESCRIPTION

FIG. 1 is a perspective view of a combined snowmobile ski and handle of my new design;

FIG. 2 is a top plan view thereof;

FIG. 3 is a side elevational view thereof, the opposite side being a mirror image thereof;

FIG. 4 is a bottom plan view thereof;

FIG. 5 is an enlarged front elevational view thereof;

FIG. 6 is an enlarged rear elevational view thereof;

FIG. 7 is an enlarged side elevational, partly sectioned, of the front of the snowmobile ski and handle of FIG. 1;

FIG. 8 is an enlarged sectional view taken along line 8—8 of FIG. 2;

FIG. 9 is a perspective view of a modification of the combined snowmobile ski and handle of FIG. 1;

FIG. 10 is a top plan view of FIG. 9;

FIG. 11 is a side elevational view of FIG. 9, the opposite side being a mirror image thereof;

FIG. 12 is a bottom plan view of FIG. 9;

FIG. 13 is a front elevational view of FIG. 9;

FIG. 14 is a rear elevational view of FIG. 9;

FIG. 15 is an enlarged side elevational, partly sectioned, of the front of the snowmobile ski and handle of FIG. 9; and, FIG. 16 is a sectional view taken along line 16—16 of FIG. 10.
